UNITED STATES PATENT OFFICE.

WILLIAM F. CAMERON, OF OGDEN, UTAH.

GOVERNOR-VALVE.

1,165,315.

Specification of Letters Patent. Patented Dec. 21, 1915.

Application filed October 31, 1914. Serial No. 869,699.

To all whom it may concern:

Be it known that I, WILLIAM F. CAMERON, a native-born citizen of the United States, residing at Ogden, in the county of Weber 5 and State of Utah, have invented new and useful Improvements in Governor-Valves, of which the following is a specification.

The invention relates to an improvement in governors and particularly in a double 10 acting governor in that it will automatically cut off the steam from the engine when at rest or under speed limit to which it has been set, whereby in the event of accident to the governor or the mechanism operating the 15 same, the engine will be prevented from racing.

The main object of the present invention is the provision of a governor carrying a double valve structure for each steam opening 20 controlled by the governor, the valve being arranged so that the governor may control the passage of the steam through the opening when the governor is at rest or at the maximum movement for which it has 25 been set.

The invention in the preferred form of details will be described in the following specification, reference being had particularly to the accompanying drawings, in which:—

30 Figure 1 is a sectional view illustrating the improved governor. Fig. 2 is an enlarged sectional view of the steam and tubing therefor, whereby the valves are removably secured to the stem in the convenient manner. Fig. 3 is an enlarged plan illustrating particularly one of the communicating openings between the chambers of the 35 governor shell.

In carrying out the present improvement, 40 it will be understood that the governor above the shell or steam casing 1 thereof is of any usual or preferred construction, and that in this particular I contemplate the use of any desired or appropriate type of operating 45 mechanism. As usual, the shell 1 is divided into an outer chamber 2 into which the steam is admitted at 5 and an inner chamber 4 from which the steam is delivered to the engine through an opening 3. The chambers 50 2 and 4 communicate through upper and lower openings 6 and 7, and in the usual type of governor these openings are controlled by valves adapted when the governor has reached a predetermined speed to cut off the 55 means of communication and so throttle down the engine.

The stem 8 of the governor is of the usual construction and for the purposes of my invention I secure thereon sleeve sections 9 and 10 disposed in superimposed relation 60 upon the stem and secured through the medium of threads, as illustrated. Each sleeve section has a circumferentially enlarged cylinder portion 11, the enlargements coöperating respectively with the openings 65 6 and 7. Each opening is provided with a removable valve seat 12 having a central guide member 13 supported through the medium of spokes 14 from the valve seat ring 12, the guide 13 slidably receiving enlarged portions 70 11 of the sleeve sections, whereby to guide the stem in its reciprocatory movement. Each sleeve section above and below the enlargement is threaded at 15 to receive a valve, the valves being designated as 16, 75 17, 18 and 19, the valves 16 and 17 being thus arranged respectively above and below the openings 6, while the valves 18 and 19 are similarly arranged with respect to the lower opening 7. Each valve is preferably 80 provided with a clamping extension 20 of slotted formation, with which a clamping nut 21 coöperates, whereby the valve may, after being properly seated upon the stem section, be secured in place against the possibility of movement.

As thus described, it will be obvious that the valves 16 and 17 are arranged for opposite coöperation with the opening 6, a similar result brought about by the valves 18 and 85 19 with respect to the opening 7, that is to say that the valves 16 and 18 will close the openings 6 and 7 when the valve stem is at its highest limit of movement, while the valves 17 and 19 will close the openings 6 95 and 7 when the valve stem is at its lowest limit of movement.

The chambers 2 and 4 are further communicating through a port 22 located at one side of the opening 7 and controlled through 100 an appropriate valve 23 operable through any shell.

Under the maximum predetermined speed of the governor, the valves 16 and 18 will close the respective openings 6 and 7 to 105 throttle the engine, while in the event the governor becomes inoperative from any cause, the valves 17 and 19 will similarly close the opening. Therefore the governor is of double acting type and will automatically 110 cut off steam from the engine in either extreme positions of the governors. In

starting the engine, after cessation of the governor operation, the valve 23 is operated to admit steam to the engine independent of the openings 6 and 7, thereby giving the engineer control of the dead engine independent of the governor.

What is claimed is:—

A double acting governor valve including an operating stem, sleeve sections removably

secured to said stem, and spaced oppositely 10 acting valves carried by each sleeve section. In testimony whereof I affix my signature in presence of two witnesses.

WILLIAM F. CAMERON.
